UNITED STATES PATENT OFFICE.

PERCIVAL P. BEBRY, OF BROOKLYN, NEW YORK, ASSIGNOR TO THE ENGLANDER SPRING BED COMPANY, OF BROOKLYN, NEW YORK, A CORPORATION OF NEW YORK.

BEDIVAN.

Application filed November 5, 1921. Serial No. 512,997.

To all whom it may concern:

Be it known that I, PERCIVAL P. BEBRY, a citizen of the United States, residing at Brooklyn, in the county of Kings and State 5 of New York, have invented certain new and useful Improvements in Bedivans, of which the following is a specification.

This invention relates to a combination bed and divan and in the present instance 10 will be designated as a bedivan, the object of this invention being to provide an improved structure of this general class comprising in a general way a main or stationary section, a sliding section, and a swing- 15 ing back connected to said main section and to said sliding section whereby on lowering the back, the sliding section will be shifted forward from under the main section and raised into a position to bring it substan- 20 tially level with the main section, and upon raising the back to its upright position the sliding section will be drawn in under the main section and lowered together with suitable self locking means for maintaining 25 the back in its upright position, the several sections being so constructed and organized that a very compact, easily operated, bedivan is provided, the linkage connections between the same being such that 30 upon unlocking the back the same will fall of its own weight and simultaneously shift the sliding section into its forward position, whereupon the structure forms a full length bed in the direction of movement of the 35 sliding section and when the back is lifted it will form a divan of pleasing and attractive appearance. One of the objects of the invention therefore is the provision of a three-section bed of the character described 40 in which the linkage connections are so constructed and located that the weight of the back itself will shift the sliding section while at the same time providing a structure of the character described in which the linkage 45 connection will be very simple and not liable to get out of order, and which structure will take up comparatively little space when in the form of a divan and no greater wall space when converted into a full length 50 bed.

In the drawings accompanying and forming a part of this specification Fig. 1 is an end view of this improved bedivan, a portion of the back being illustrated in dotted lines in its upright position; Fig. 2 is a top

view of the present improvement with the spring fabrics broken away; Fig. 3 is an end view of the structure closed to divan form; Fig. 4 is a view of the structure shown in Fig. 3 from the rear or back side 60 thereof; Fig. 5 is a view of the structure shown in Fig. 1 from the front side thereof; and Figs. 6 and 7 illustrate this improved bedivan in its closed and open positions when supplied with the usual mattress and 65 covering. Similar characters of references indicate corresponding parts in the several views.

In the preferred form thereof herein shown and described, the main section of 70 the bed 20 comprises a pair of end frames 2, each consisting of a horizontal end bar 3 and a pair of uprights or legs 4 and 5. Each of the end frames in the present instance is shown as of angle iron construc- 75 tion, and the two front legs and also the two rear legs are connected by a suitable framework or truss-work 6 and 7 whereby they are properly stiffened and the spreading thereof prevented, this truss-work 6 at 80 the front and 7 at the rear including what may be termed lengthwise extending side bars 8 and 9 respectively. These end frames are suitably connected by a metallic fabric stretched therebetween usually by means of 85 coiled springs. The sliding section 30 likewise comprises a pair of similarly formed end frames 9', each end frame having a pair of depending legs 10 and 11, the inner ones of which however, as 11 being shown 90 shorter than the outer ones, and these two end frames are likewise truss connected in the manner heretofore described. The end frames of the sliding section also have a metal fabric 12 stretched therebetween. 95 The rear legs at each end of the sliding section are connected with the horizontal angle bars thereof by a curved brace 13 which acts as a cam by its engagement with the lengthwise extending side bar 8 connecting 100 the two front legs of the main section. In other words the metal fabric and the horizontal bars to which it is connected are located between the side bar 8 and the metal fabric of the main section so that when the 105 sliding section is shifted forward from under the main section these curved bars act as cams in connection with the front side bar and gradually raise the front section so as to bring the rear side thereof level 110

with the front side and for which purpose the legs at the rear of the sliding section are raised from the floor, these being shorter than the legs at the outer end of the sliding section.

By thus raising the sliding section the metallic fabric thereof will be brought up close to the metallic fabric of the main section so that they will be practically level with each other and thus present an even surface to sleep upon. Connected to the end frames of the main section at the rear side thereof is the swinging back 40 which comprises likewise a pair of end members 14 connected at their outer ends by a transversely extending member 15. These end members 14 carry a suitable fabric 16 stretched therebetween and are pivotally connected as at 17 to the end members of the main section 20 in such position that when the back is lowered it will be level with the main section. Suitably pivoted to the end members 14 of the back are a pair of legs 18, link connected by suitable links 19 with the rear legs of the main section. Riveted to the inner end of each of the end members 14 of the swinging back 40 is a forwardly extending bar 21, which bars 21 are connected together at their front ends as at 22. This yoke-shaped member 21—22 is shown in the present instance as of tubular form and of such weight as to act as a counter-balance to the swinging back. The bars 21 of the swinging back are provided with a pair of riveted plates or bars 23 to the forward ends of which are pivotally connected a pair of links 24 which in turn are pivotally connected to the end bars of the end frames of the sliding section 30, so that the yoke 21—22, together with the links 24 constitute the means for shifting the sliding section forward and rearward relatively to the main section while the legs 18 of the swinging back are so located that on lowering the back they will fall into position to properly support the back in its horizontal position, and on raising the back they will automatically position themselves up close against the rear of the back.

The construction is such that the weight of the back will automatically lower it and locking means is provided therefor for maintaining the back in its upright divan-forming position, and in the present instance this locking means is a pedal releasable means and is of very simple construction. This locking means comprises a locking member or bar 25 provided with a pair of slots 26 for the reception of headed pins 27 carried by the truss frame at the rear of the main section. The lower end of this locking bar is so shaped that it will engage the top face of the counter-balancing bar 22 and prevent it from moving forward and thus prevent the back from falling down.

To release the locking bar, a pair of levers 28 are pivotally connected to the bar one above the other and are also pivotally connected as at 29 to a part of the truss frame, and the outer ends of these levers 28 are provided with angle extensions 31 forming foot engaging means whereby the locking bar may be released at either side of the bed. In other words by pushing on the ends 31, the bar is raised, thus unlocking the yoke-shaped member 21—22 whereupon the weight of the back lowers it, which operation as hereinbefore stated, shifts the sliding section forward from under the main section. By raising the back the sliding section is drawn under the main section and the locking bar falls of its own weight and engages the forward member 22 of the yoke-shaped member and so automatically locks it in position and consequently the back in its upright position. As hereinbefore explained when the sliding section is shifted forward, the diagonal braces 13 slide over the edge of the front side bar 8 of the main section and raise the rear end of the sliding section to a position where it will be level with the front end of the sliding section so that its spring mattress will form substantially a continuation of that of the main and swinging back sections and thus form a full length bed.

The legs 18 are suitably braced by a cross member 32 and in the form of structure shown the various corners of the main and sliding sections are brace-connected as for instance at 33 especially when they are formed of angle iron. From the foregoing it will be observed that, other than the links which connect the legs 18 of the swinging back to the legs of the main section, the only link connections in the entire section is that between the swinging back and the sliding front section, which links constitute the extensions of the yoke-shaped bar which in turn constitute extensions of the end members of the swinging back so that the structure is very simple in its organization, as well as rigid and comfortable in use.

In the present instance the front sliding section is shown somewhat narrower than the main section and the legs are provided with suitable castors to facilitate the shiftable movement thereof, while the legs of the main section may be provided with "domes of silence" to facilitate the movement of the entire structure when this is necessary. In practice of course the bedivan is provided with suitable mattresses of book form arrangement, one for the back, one for the main section, and one for the sliding section, that of the sliding section being foldable over that of the main section when the sliding section is drawn under the main section, and the whole is suitably covered by an ornamental covering such as cretonne

or other suitable material, whereby the bedivan presents an attractive appearance, takes up a comparatively small amount of room and at the same time when 5 transformed into a three-section bed it provides a suitable structure to sleep upon.

From the foregoing it will be seen that the manipulation of the sliding section is obtained by the operation of the swinging back which automatically falls on releasing the locking member from the yoke-shaped member 21-22 so that without the use of 10 the hands at all, the operator by merely placing his foot upon the releasing levers 28 and releasing the lock bar, permits the 15 divan to automatically transform itself into a full length bed, and that to transform it into a divan it is merely necessary to raise the back until the lock engages. Consequently 20 the structure is not only simple in operation but can be very readily handled by a child or a woman without the lifting of any heavy parts, especially as the yoke acts as a counter-balancing means for the 25 back and assists materially in the raising of the back.

It is to be understood that the various details may be more or less changed without departing from the spirit or scope of the 30 invention.

In conclusion it will be seen that a very simple convertible bed structure is provided comprising a shiftable front section, a main section, and a swinging back section, which 35 latter when released automatically positions itself level with the main section and at the same time automatically operates the shiftable front section into position also level with the main section, thereby converting 40 the structure from a divan into a full length bed, while the means for locking the back in its upright position is a self locking means, that is an automatically operative locking means releasable from 45 either end of the bed.

I claim as my invention:

1. In a bedivan the combination of a main section, a sliding section shiftable beneath the fabric of the main section, a swinging 50 back section connected with the sliding section for shifting it, locking means, counterbalancing means for the back shiftable with the sliding section and cooperating with said locking means for maintaining the back in an upright position, and pedal means for releasing said locking means.

2. A bedivan comprising a main section, a sliding section, a swinging back section hinged to said main section, swinging 55 counterbalancing means therefor, means connected to said swinging counterbalancing means and with the sliding section whereby the latter is shifted at predetermined times by the swinging back section and the swinging counterbalancing means, locking means

cooperating with said counterbalancing means for maintaining the back in position, and pedal means for releasing said locking means.

3. In a bedivan the combination of a 70 main section, a sliding section, a swinging back section, counterbalancing means for the back section, locking means cooperating with the counterbalancing means for maintaining the back in position, and pedal 75 means for releasing said locking means.

4. A bedivan comprising a main section, a sliding section, a swinging back section hinged to said main section, a forwardly extending yoke rigidly connected to the back section, means for locking said yoke and thereby the back section in its upright position, and means connecting the yoke with the sliding bed section, the construction being such that on the releasing of the locking means the back will fall of its own weight and automatically shift the sliding section.

5. A bedivan comprising a main section, a sliding section, a swinging back section 90 hinged to said main section and adapted to fall into a horizontal position by its own weight, means for supporting it when in a horizontal position, means connecting it with the sliding section whereby the latter will 95 be shifted on the falling of the back section, and locking means for locking said back section in its upright position and comprising a sliding bar, a pair of oppositely extending lever members for shifting said bar, said bar having locking means cooperating with said connecting means.

6. In a bedivan the combination of a main section, a sliding section, a swinging back section connected with the sliding section 105 for shifting it, locking means carried by one section and located intermediate the ends thereof, and means shiftable into engagement with the locking means upon swinging the back section for automatically locking the back section in position, and means for releasing said locking means.

7. In a bedivan the combination of a main section, a sliding section, a swinging back section hinged to the main section and connected with the sliding section for shifting it upon swinging the back section, locking means for maintaining the back section in upright position and comprising a shiftable latch carried by one of the sections and located beneath the same and between the ends thereof, and means connected to one of the sections for engaging the latch, said latch and means being one shiftable into engagement with the other by swinging the back section.

8. A bedivan comprising a main section, a sliding section, a swinging back section hinged to said main section and connected 125 with the sliding section for shifting it, lock- 130

ing means carried by the main section adjacent to the rear thereof for maintaining said back in its upright position and comprising a vertically slidable locking bar, and 5 pedal means for sliding it.

9. A bedivan comprising a main section, a sliding section, a swinging back section hinged to said main section and provided with a forwardly extending bar, means connecting said bar with the sliding section whereby the latter is shifted by the swinging back section, automatically operative locking means in position to engage said bar thereby to maintain the back in its 10 upright position, and means for releasing said locking means from said bar.

10. A bedivan comprising a main section, a sliding section, a swinging back section hinged to said main section and provided 20 with a forwardly extending bar, means connecting said bar with the sliding section whereby the latter is shifted by the swinging back section, automatically operative locking means in position to engage said 25 bar and located below the plane of the mattress portions thereby to maintain the back in its upright position, and means for releasing said locking means from said bar.

11. A bedivan comprising a main section, 30 a sliding section, a swinging back section hinged to said main section, means connecting the swinging back section with the slid-

ing section whereby the latter will be shifted on the falling of the back section, and locking means cooperating with said connecting means for automatically locking the back in its upright position, and means for releasing said locking means from said connecting means.

12. In a bedivan the combination of a main section, a swinging back section hinged thereto, a sliding section shiftable beneath the fabric of the main section, a counterbalancing bar rigidly connected to said back section, converging levers connecting said counterbalancing bar with the sliding section, said counterbalancing bar having a swinging movement beneath the main section while the sliding section slides beneath the fabric of the main section.

13. In a bedivan the combination of a main section a sliding section shiftable beneath the fabric and between the ends thereof, a swinging back hinged to the main section and movable with the sliding section, a swinging U-shaped counterbalancing bar rigidly connected to the back and so connected with the sliding section as to swing beneath the fabric of the main section as the sliding section slides therebeneath.

Signed at Brooklyn this 2nd day of November, 1921.

PERCIVAL P. BEBRY.
